SECTIONAL CONTAINER FOR TOILETRIES OR THE LIKE

Victor J. Terre, 1023 Adams Ave.,
Union Township, N.J. 07053

Filed May 1, 1967, Ser. No. 6,890

Term of patent 3½ years

Int. Cl. D9—01

U.S. Cl. D9—18

FIG. 2

FIG. 1 is a perspective view of a sectional container for toiletries or the like showing my new design, the opposite side being substantially the same in appearance as the side shown; and

FIG. 2 is an enlarged sectional view thereof taken on the line 2—2 of FIG. 1 the side opposite to that seen in FIG. 1 is the same in appearance as the side shown.

I claim:

The ornamental design for a sectional container for toiletries or the like, as shown and described.
